(57) **CLAIM**

I claim the ornamental design for a shopping trolley with basket, as shown and described.

DESCRIPTION

FIG. 1 is a front perspective view of a shopping trolley with basket showing the new design;

FIG. 2 is a rear perspective view thereof;

FIG. 3 is a left side view thereof;

FIG. 4 is a front end view thereof;

FIG. 5 is a rear end view thereof;

FIG. 6 is a top view thereof; and,

FIG. 7 is a bottom view thereof.

The broken lines in the drawings depict portions of the shopping trolley with basket that form no part of the claimed design.
